Application October 9, 1952, Serial No. 313,912

15 Claims. (Cl. 62—104)

1

This invention relates to the cooling of canned produce immediately after having been packed and sealed in large commercial production, such as a packing house, and is an improvement upon the method and apparatus disclosed in United States Letters Patent No. 2,477,992.

In packing plants that process edible products and pack them in cans or jars, it is customary to transfer the containers from a sealing or closing machine to a cooling apparatus to reduce the temperature of the container, and its contents, to approximately that of room temperature so as to avoid, so-called, "stack-burn" and to enable the cans or containers to be labeled and packed for shipping.

The cooling apparatus conventionally used for this purpose, during approximately the past decade or more, includes a moving belt upon which the containers may be spun about their axes, a conveyor means positioned immediately above the belt for moving the containers along the length of the belt, and a device for spraying cold or cool water onto the cans to cool the surfaces thereof, the belt being driven at a faster speed than the conveyor so that the containers will be caused to revolve rapidly to agitate their contents in contact with the cooled walls of the container.

Prior to the employment of the aforesaid conventional cooling apparatus, some attempts were made to cool cans by the employment of a spinning belt but, if the belt was horizontally level, it was found that the cans would not spin but be conveyed through the apparatus without spinning about their axes to any material extent; and, if one end of the belt was elevated so as to incline the belt, the cans would be spun but would not progress along the belt in the direction of the travel of the belt and discharge therefrom, thus remaining in the apparatus. As a result the, so-called, bar conveyor, shown in the aforementioned patent, was employed in one form or another to advance the containers through the cooling apparatus while spinning them by the underlying belt to agitate and quickly cool their contents. The type of cooling apparatus, exemplified by the aforementioned patent, has functioned very well and a considerable number are now in use; however, the utilization of the conveyor—comprising a pair of spaced parallel chains driven over sprockets and having transverse bars connected between their length at spaced intervals—adds considerably to the original cost of the machine and their maintenance is very high as the chains were continually exposed to the corroding action of the cooling water.

We have found that exceptional results may be obtained in a can cooling apparatus, employing a spinning belt and a water cooling medium only, by arranging the container supporting reach or flight of the spinning belt at an inclination of

2

about $\frac{1}{2}$ inch elevation to the running foot of said flight and providing at intervals along said flight a plurality of, so-called, check-gates which allow the containers, being advanced and spun by said flight, to pass thereunder but which will prevent the cans from rolling back beyond said check-gates at any time they lose sufficient frictional traction with the belt to advance forwardly and upwardly of the inclined surface of said flight of the belt.

This discovery permits the elimination of the, so-called, bar conveyor overlying the belt and its attendant cost and maintenance. We have also discovered that with the improvements of this invention a hot can, and its contents, can be cooled to a temperature of approximately 100° F. or less, from a temperature of approximately 200° F., more or less, in about one-half of the time required by the so-called conventional can cooling apparatus. Thus, where the aforementioned conventional can cooling apparatus for cooling a given product may require an apparatus sixty feet in length, the present invention permits the same to be done in an apparatus about one-half the length, the canned produce progressing through both machines at about the same speed. Obviously, greater production at less cost than heretofore is obtained.

It is common knowledge in the produce packing art that certain packed edibles, which are semi-liquid or contain more solid mass content (such as canned sliced apples, peaches, pears, pineapples, grapefruit, beans and the like) require a greater time element for cooling than do liquid products such as vegetable and fruit juices, because the solids within the container are more difficult to agitate and their contained heat is given up at a slower rate. We have found further that by causing the containers to reverse positions endwise several times, during their passing through the cooling apparatus, their solid contents are caused to better shift positions to bring the warmer foods in the center of the cans to mix with the cooler foods at the outer surfaces of the can (or, stated another way, the previously cooler contents moved toward the center of the can) and a more uniform and quicker heat transfer is obtained than by only spinning the can.

The object of the present invention, therefore, is to provide an improved method and apparatus for effecting a much greater heater transfer efficiency in the cooling of sealed cans and their contents and to attain this with much simpler and less expensive instrumentalities, both in original cost and in maintenance, than has heretofore been possible and in about one-half the time, thus requiring a cooling apparatus of one-half the size than heretofore.

Other objects and novel features of the present

invention will be apparent from the following detailed specification.

A more detailed understanding of the manner in which the present invention may be accomplished can be ascertained from the following description of the present embodiments thereof as now actually employed and which are illustrated in the accompanying drawings, wherein:

Figure 1 is a side view in elevation of one unit of the can-cooling apparatus of the present invention, the other unit being fragmentarily shown in side elevation and as connected with the first unit by means of an end-twister for the cans;

Figure 2 is a diagrammatic side view in elevation of the basic working elements of one unit of said can-cooling apparatus;

Figure 3 is a cross-sectional view taken transversely through one unit of the apparatus substantially on line 3—3 of Fig. 1;

Figure 4 is a fragmentary longitudinal sectional view of one unit of the apparatus taken substantially on line 4—4 of Fig. 3 and looking downwardly in the direction of the arrows shown;

Figure 5 is a fragmentary plan view of the bottom of the drip pan showing the preferred type of openings therein;

Figure 6 is a cross view of the bottom of said drip pan and taken substantially on line 6—6 of Fig. 5;

Figure 7 is a longitudinal sectional view taken substantially on line 7—7 of Fig. 4 to illustrate the detail construction of the mounted check-gates for the cans; and

Figure 8 is a transverse sectional view showing a modified construction for a can cooling unit of this invention.

Like characters of reference throughout the specification and drawings refer to similar and like parts.

The present invention may be carried into practice with a cooling apparatus disclosed in the aforementioned patent but, in which the can advancing conveyor 26 (as shown in said patent), and its constituent parts as well as its drive means, are eliminated.

The cooling apparatus of this invention, therefore, may comprise two units A and B (see Fig. 1) of identical construction connected by a can end-wise twister 27; and each section may comprise a trough 10 supported by legs 11 at spaced intervals along its length and positioned to be slightly upwardly inclined from its receiving or intake end to its discharge end. Within the trough 10 is disposed a flexible endless belt 12 (usually a fabric reinforced rubber belt) extending the length of the trough and having its end portions extending slightly beyond the same as shown. At the intake end of the trough 10 is a sump tank 13 into which the trough discharges and projects for a distance outwardly from said end of the trough. The sump-tank 13 has an outlet 13a for draining the same or which may be connected with a suitable recirculating system that re-cools the water and reuses it. A drum 14 is journaled transversely of the trough 10 and overlies said tank 13 and has the lower end of said belt trained thereabout; and the upper or discharge end of the belt 12 is trained about the drum 15 mounted on a supporting frame 16 positioned to support the discharge end of the trough 10. Mounted on the supporting frame 16 is a motor 17 operatively connected to a variable-speed drive device 18 connected by a chain or

belt 19 to a sprocket or pulley 20 fast on the axis of the drum 15. In practice the portion of the trough 10 supported by the frame 16 has its bottom wall cut away for a distance at its discharge end and the bottom or return reach of the belt 12, passing over drum 15, is passed over a belt-tightening device (which may comprise a horizontally adjustable roller 21 and a vertically adjustable roller 22) and, thence, to a roller 23 positioned on the framework 16 and aligned with the bottom wall of the trough 10 to direct the return flight of the belt 12 into the trough. The legs 11 may have vertically adjustable feet 11a to vary the degree of inclination of the upper or can supporting flight of the belt 12.

The tank 13 is surmounted by a framework 24 which supports a transverse can feeding belt 25 that delivers filled and sealed hot cans C in a vertical position to the cooling apparatus from a can sealing machine, not shown. A conventional can-turner 26 is provided to guide the cans from the feed belt 25 and to deliver them upon the lower end of the spinner belt 12 in a rolling horizontal position transversely of the belt.

As previously stated, the detailed construction of the correlated parts of the one or more units of the cooling apparatus, such as A and B herein shown, are identical and a description of one is a description of the other except that, in some instances, the trough 10 may extend continuously under one or more units, thus requiring only one sump-tank 13. In either case, the trough 10 may have the inner surface of its bottom wall provided with ridges, or otherwise provided with equivalent means, to contact and support the lower or return flight of the spinner belt 12 at spaced intervals to prevent undue friction between the belt and the bottom wall or the adhering of the belt thereto. The upper or can supporting flight of said belt 12 is supported by and moves over a grating 28 extending the length of said upper flight of the belt, said grating being removably disposed upon cross-bars 29 interposed between said flights of the belt 12 within the trough 10 and connected at their ends to uprights 30. There are a plurality of these uprights 30 oppositely positioned at spaced intervals along the length of the opposing sidewalls of the trough 10 for supporting the water-cooling-distributing means and the can guide means. The upper flight of the belt 12 is guided in its path of movement by guides 31 arranged on opposite longitudinal sides thereof. These guides 31 may be in the form of angle-irons having one flange fixed to said cross-bars 29 and the other flange extending for a distance above and in substantial abutting contact with said longitudinal edges of the belt 12 to preclude excessive drainage therebetween and to retain a shallow depth of water along the length of the belt.

The cans C fed into either unit A or B of the cooling apparatus are guided, as they advance through the apparatus, in one or more lanes on the belt 12 by a plurality of splash guides 32, each of which comprises an elongated strip positioned vertically edgewise and extending longitudinally of the belt. Three of these splash guides are shown in the drawings, dividing the belt into two lanes and each, preferably, is of a height to extend from a point slightly above the upper edges of the belt-guides 31 to a point above the cans being cooled. The lower longitudinal edge portions of the splash guides are outwardly flared,

as at 32^a, toward the ends of the cans so that water splashing from the cans or onto the splash guides will be directed upon or thrown back against the ends of the cans. Hangers 33, shown in the form of stud-bolts, extend at spaced intervals from the upper edge of the splash guides 32 and project through an elongated slot in supporting transverse bars 34 secured at their end to intermediate points of the uprights 30, whereby the splash guides may be adjusted transversely of the belt 12 along the slots 34^a to accommodate cans of different sizes for any given run of cans in the apparatus.

In order to cool the cans C, and their contents, water is dropped upon them, as they spin and float back and forth on the belt 25, from the spray (shown in Figure 8), or from a drip pan 35 (shown in the other figures of the drawings) overlying the belt and extending the length of the trough 10, the bottom surface of the pan 35 being perforated throughout its area overlying the belt 12 with a large number of small holes 36 which cause the water to drop on the cans in small streams or large drops. These holes or perforations 36 are preferably formed by punching only one side of a round hole and depressing the lip or tongue 37 at a slight angle so that the passages provided by the holes are not completely open, as shown in Figure 6, and are positioned or directed upstream with respect to the flow of water over the holes. By this arrangement any foreign matter carried by the water passing the openings will not lodge in the openings as the water will keep the openings unobstructed. The drip pan 35 may be supported by adjustable hangers 39, as best shown in Figure 3, and which may comprise U-shaped bolts extending upwardly through openings in cross members 40 extending between and secured to uprights 30, suitable nuts 39^a being threaded on the upper ends of the hangers to maintain them in adjusted position. The pan 35 is adapted to rest upon the depending closed or cradle end of the hangers 39 and be supported thereby.

Water is supplied to the pan 35 by a pipe 38 overlying the pan in substantially spaced relation therefrom and extending longitudinally thereof and mounted on the cross-member 40. A plurality of nozzles 41 located at intervals along the length of the supply pipe 38 maintains a shallow film or depth of water over the entire surface of the pan. This arrangement feeds the water to and allows it to drop through all of the perforations 36 in the bottom of the pan 35. It is preferred to supply the nozzles 41 from the pipe 38 by feed extension pipes 38^a tapped from said supply pipe at selected intervals along its length and which extend downwardly toward the pan 35 and are provided with a flow-regulating and cut-off valve 38^b. From the lower end of each feed pipe 38^a horizontally extends two lateral branches that terminate in T-sections or fittings 41 that are so positioned as to throw jets of water in opposite directions longitudinally of the drip pan, whereby the water is evenly fed over the bottom of the pan 35.

The above describes generally one of the apparatuses to which the present invention is applicable; and which invention comprises arranging the upper or can supporting flight of the spinner belt 12 at inclinations and driving it at speeds in accordance with the following table for different size cans and in the provision of, so-called, check-gates 42 positioned at intervals along the length of the belt to check or limit the

backward movement of the cans downward the inclined surface of the belt.

Table

5	Can Size	Belt Inclination Per Lineal Foot	Belt Speeds In Feet Per Minute	
			Range	Optimum
10	6 oz.....	½ inch.....	140-160	150
	18 oz. (No. 2).....	do.....	125-145	135
	36 oz. (No. 404).....	do.....	110-130	120

As above indicated, the most satisfactory inclination of the upper or supporting surface of the spinning belt 12 is one-half inch per lineal foot for all sizes of cans. Any material lowering of the belt beyond inclinations indicated tends to cause the cans C to be carried through the machine without the proper spinning required for cooling within the minimum length of the apparatus that it is possible to cool said cans. However, if the inclination of the belt is materially more than about three-fourths of an inch grade per linear foot, the cans will not be moved through the cooling unit by the movement of the belt, but, after a certain number of cans have crowded upon the intake end portion of the belt, they will remain there and be merely spun thereby, this being apparently because the pressure of the oncoming can from the feed belt is insufficient to push the cans on the belt upwardly of the incline to the discharge end of the belt; hence the previous need for a positive conveyor for the cans. When the belt is so positioned, as just indicated and operated at the proper speed for a given size can in accordance with the above table, the cans C being delivered to the lower end of the belt, from the can turner 26 or from the can twister 27, will roll upon the belt and commence their spinning operation (in the direction of the arrow shown). So far as can be determined, due to their frictional contact to the belt in addition to the urge given by the crowding of oncoming subsequent cans delivered to the belt, the can C will progress erratically and upwardly of the belt at a slower rate of speed than the movement of the belt itself and be discharged from the discharge end of the belt. The effect of this erratic action of the cans C appears to cause them, and their contents, to cool more quickly.

From observation, it has been observed that, at the receiving end of the belt 12, the cans will most frequently be in close contact for a short distance and from that point on will start the erratic action mentioned, while being spun by the belt in the shallow stream of water flowing down the belt and being subject to the dripping action or spray of water from the water pan 35 and the action of the splash guides 32. When a can is delivered to the belt from the turner 26 or the twister 27, it has been observed that the can, which may be contacted thereby at the lower end of the belt, may stop spinning momentarily, as well as all other cans in immediate sequential contact, and progress forwardly on the belt for a short distance, while at the same time resuming their spinning, and pass through the cooling unit, some separating from close contact one against the other and advancing further along the belt for a distance and, then, apparently losing traction and rolling back down the belt until they abut another can or a check-gate 42. Thereafter, one or more cans again

will resume their progress forwardly and upwardly along the belt in close contact or may move out of contact with the adjacent oncoming cans. The action of each individual can on the belt is not predictable but generally follows the pattern just described. Nevertheless, the cans will be spun rapidly by the belt and intermittently progress along the belt forwardly and, then, move down the belt and, then, move forwardly again.

Therefore, it is assumed that the inclination of the belt in addition to the action of the oncoming cans onto the belt supply that frictional friction so necessary to give the cans that intermittent forward and backward movement, while being spun, to agitate the contents of the cans to quickly cool them and to progress gradually forward through the cooling unit without the need of a positive can conveyor.

This progressive forward movement of the cans C through the cooling unit of this invention or discovery appears, however, to be dependent upon the check-gates 42 in order to prevent cans that have advanced from the intake end of the apparatus from rolling back too far against the cans at the lower end of the belt. Therefore, the check-gates 42 are provided at spaced intervals (approximately five feet apart) along the length of the belt, beginning at about five feet from the point a can is delivered to the belt 12, and are constructed to allow the cans to pass thereunder, by their own momentum, but which will stop the backward or rolling movement of the cans beyond the said check-gate, yet will allow a back and forth float movement of the cans between adjacent check-gates.

While the belt speeds, above indicated, have been found satisfactory to produce the results stated, it is possible that the optimum speeds may be varied for containers having contents of different consistencies in order to obtain the action above described.

The check-gates 42 are arranged in each lane and each may, and preferably does, comprise a U-shaped rod having its closed end journaled in a sleeve 43 carried on a plate 44 that is removably fastened, as by bolts and nuts fasteners 46, to each of the cross bars 34. The legs of the U-shaped member 42 extend in the direction of the movement of the belt and have their distal extremities extending arcuately downward toward the belt 12 so that its under concaved side may be contacted by an advancing can on the belt and be raised by the momentum of the can in order to allow the can to pass thereunder and therebeyond. Immediately after a can has passed under the arcuate extremities 42a of the check-gate, it drops by gravity to a position with its lower ends slightly out of contact with the top surface of the belt 12 and is held in this position by lateral stops 43a on the ends of the sleeve 43. These stops may comprise an adjusting screw s threaded in a lug l on the ends of the sleeve 43. Of course, the lower extremities of the check-gate 42 may rest upon the belt 12 but, over a period of time, the friction may groove the belt and cause its quicker deterioration. Cans that have passed beyond a check-gate 42 may later lose their frictional grip on the belt and roll down the belt again and abut the convex side of the legs 42a of the check-gate and be stopped thereby. This momentarily stops the spinning of the can and allows it to gain its frictional or frictional grip on the belt to progress forwardly again while being spun there-

by in a direction opposite to its forward progress through the apparatus.

The opposite legs 42a of the check-gate should be separated apart sufficient to engage the can near its opposite ends—i. e., each of the legs should engage the cans at a point approximately midway between the ends of the can and its center, when the can is a horizontal position. For different size cans, different check-gates, having their leg portions 42a properly spaced, may be inserted in place upon the cross bar 34.

A previously indicated, a cooler unit constructed as above and including the above improvement will cool cans in approximately one-half the time that they may be cooled with similar coolers employing the can conveyor (disclosed at 26 in the aforesaid Letters Patent) and, for containers containing a liquid content, such as fruit and vegetable juices, only one unit, such as A in Figure 1, is sufficient and may not be more than thirty feet in length as against fifty to sixty feet heretofore, thus conserving valuable floor space. In this event, the twister 27 will not be employed but a can take-off may be provided similarly as shown in the aforesaid Letters Patent and indicated by the parts 66 and 65 thereof.

Containers containing more solid contents, may be cooled more quickly if, after a preliminary cooling in unit A of the apparatus shown in Figure 1, they are passed through a double twister 27 which will shift the can endwise in opposite directions, as stated above, and then pass it to a second unit B of the apparatus, the unit B being the same as unit A. However, if when the machine is made in two or more units, the length of each unit of the machine may be materially shortened, in some instances, to fifteen or twenty feet in length each.

A twister 27 is provided for each lane of can C on the spinning belts 12 and is what is known as a double-twister. Each twister 27 is of conventional construction comprising spaced co-extensive narrow strips a of metal or rigid material formed to guide and change the position of the cans C as they pass therethrough under their own movement usually by gravity. Each double-twister 27 is essentially two single twistlers t and t' jointed end-to-end in tandem, one twister t being formed to turn a can C endwise in one direction and the twister t' being formed to turn the can endwise in the reverse or opposite direction. Each single twister t and t' is shown as being formed to turn a can endwise 180° but it is within the purview of this invention that each single twister be capable of turning the can 360° or that more than two single twistlers t or t' be employed. Also, as shown in Figure 1, the twister 27 is arranged to receive cans in their horizontal rolling position from the discharge end of belt 12 of unit A and is inclined downwardly to deliver the cans C to the intake end of belt 12 of unit B, which is at a lower level, in a horizontal rolling position.

In Figure 8 is shown a modified form of cooling unit with which the invention has performed satisfactorily. In this form of the invention the splash guides 32 and the drip pan 35 have been eliminated. The upper surface of the upper flight of the belt 12' has been divided in two lanes by a stationary can guide 50 disposed above an intermediate portion of the belt and the belt edge-guides 51 have been made higher than the similar guides 31. Overlying each lane of the belt and extending longitudinally thereof is a water pipe 52

extending the full length of the cooler and having disposed thereover in spaced relation therewith an arcuate hood 53, the pipe 52 having a plurality of perforations 52a in its upper side adapted to direct water against the undersurface of the hood, from which hood the water drops down upon the cans below. The hood 53 is of such dimensions as to span the area of its lane in order that the water dropping therefrom will contact the entire area of the cans passing beneath them. The hoods 53 may be supported in the position shown by any suitable means such, for instance, as bracket arms 54. The upper and can-supporting surface of the spinning belt 12' is, of course, arranged at the same inclination or inclinations as previously mentioned for 12, shown in Figs. 1, 2 and 3; and check-gates 42 are similarly employed at spaced intervals along the path of movement of the cans C on said belt, the check-gates 42 in Fig. 8 being illustrated in their partially raised positions as when a can is beginning to pass thereunder. A water collecting trough 10a is disposed along the lower portion of the apparatus under the grating 28 for the same purpose as trough 10 shown in Figs. 1, 3 and 4; and the return flight of the belt 12' may be brought through said trough. This type of apparatus is very economical to construct and embodies the principles of the invention above stated; however, this constructed machine is usually made for cans of one size.

As an indication of the advantage of this apparatus over prior devices it may be said that, with a cooling water averaging about 85° F., cans of the size No. 404 have been cooled in 3½ minutes whereas it has required 7 minutes in the older type cooler to reduce the temperature from 195° F. to 97° F. in each instance; and in the case of 6 oz. cans, they are cooled to the same temperature within 1 minute 18 seconds, whereas it has required 2½ minutes in the older type of coolers. It may also be stated that the speeds of the belt given in the above table are only recommended speeds and are not to be considered as limiting, because these speeds may be varied depending upon conditions in any plant or the size of and the consistency or weight of the contents of the cans.

Having thus described the invention and the manner in which the same is to be performed it is to be understood that the invention is susceptible to various variations from the exact arrangement and performance above recited and that the invention is not to be limited except in accordance with the spirit thereof and the scope of the appended claims.

What we claim, as new, and desire to secure by Letters Patent is:

1. The method of changing the temperature of the contents of packed rollable containers comprising delivering said containers in a sequential flow onto the lower end of an inclined flat planarly-moving surface and in a position to roll in the direction of movement of said surface, causing said surface to move upwardly to its inclination at a speed to rapidly spin said containers about their own axes and to advance them without the aid of other conveying assistance, along and in the direction of the movement of said surface while permitting said containers to periodically and erratically move back and forth along and relative to the line of movement of said surface; arresting said backward movement of the containers at spaced intervals along said surface to permit said containers to regain sufficient frictional traction with said moving surface to ad-

vance forwardly and upwardly thereof; and directing a cooling medium upon said containers during their movement on said surface.

2. The method set forth in claim 1 wherein the inclination of said surface is arranged at substantially one-half to substantially three-quarters inch elevation for each linear foot thereof and said surface is moved at speeds varying approximately between 110 to 160 feet per minute.

3. The method of changing the temperature of the contents of packed rollable containers comprising passing said containers in a sequential flow and successively onto an inclined planarly moving surface and in a position to roll thereon in the line of movement of said surface; causing said surface to move upwardly of its inclination at a speed and at an inclination to rapidly spin said containers about their own axes and to advance upwardly along the surface, in the direction of the movement thereof, while permitting said containers to move periodically downward of said surface, arresting said downward movement of said containers down the belt at substantially spaced intervals in their downward movement; directing a cooling medium upon the containers during their travel on said belt; and turning said containers endwise at an intermediate point in their advancing travel along said surface to agitate the contents of said containers endwise of the latter.

4. The method set forth in claim 3 wherein said endwise turning step of said containers comprises causing said containers to move about an axis transversely of said containers successively to opposite endwise positions to agitate their contents endwise, and then again delivering said containers in said rollable position onto a said inclined moving surface.

5. An apparatus for changing the temperature of the contents of packed rollable containers, comprising a supporting frame, a conveyor mounted on said frame and having a plane inclined surface adapted to receive said containers in a rollable position thereon, means directing a cooling medium upon the containers on said belt, means for moving said receiving surface of the belt upwardly of its inclinations to cause said containers to spin about their own axes, the inclination of said surface of the belt being such as to advance said containers along the belt in the direction of its movement while being spun by said belt, with an erratic back and forth motion relative to the line of movement of the arresting belt, and means operatively mounted on said frame at points along the path of travel of said containers to allow said containers to pass thereby in their said advance along said belt and to limit the backward movement of any of said cans downward of said belt, the spacing of said arresting means being such as to allow said back and forth movement of said containers therebetween for a substantial distance of the belt.

6. An apparatus for cooling hot-packed rollable containers, and their contents, comprising an inclined belt having a surface adapted to receive said containers in a rollable position thereon, a water distributing device overlying said belt along its length and positioned to direct water upon the containers on said belt for substantially the length of said belt, variable speed means for moving said belt upwardly of its inclinations to cause said containers to spin about their own axes, and means fixedly positioned at spaced intervals along the length of said belt and movably mounted to allow said containers to

11

pass thereby in their said advance along said belt and normally biased to a position for limiting the backward movement of any of said containers downward of said belt, the inclination of said belt being such as to advance said containers along the belt in the direction of its movement, while being spun by said belt, with an intermittent back and forth movement between said limiting means.

7. An apparatus for cooling hot-packed rollable containers, and their contents, comprising an inclined belt having a surface adapted to receive said containers in a rollable position thereon, means directing a cooling medium upon the containers on said belt, means for moving said belt upwardly of its inclinations to cause said containers to spin about their own axes, the inclination of said belt being such as to advance said containers along the belt in the direction of its movement, while being spun by said belt, with an intermittent back and forth movement, and check-gates mounted on the apparatus and overlying said belt at spaced intervals along its length, each check-gate including a pivoted member declining toward said belt in the direction of the movement of said belt and into the path of said containers, thereby to allow said containers to pass thereunder in their said advance along said belt, the distal end of each member being formed to provide an abutment limiting the backward movement of any of said containers downwardly of said belt.

8. An apparatus as claimed in claim 7, wherein said check-gates further include an adjustable stop means to limit the downward movement of the distal end of said pivoted member with respect to said belt.

9. An apparatus for cooling hot-packed rollable containers, and their contents, comprising an inclined belt having a surface adapted to receive said containers in a rollable position thereon, means directing a cooling medium onto the containers on said belt, means for moving said belt upwardly of its inclinations to cause said containers to spin about their own axes, the inclination of said belt being such as to advance said containers along the belt in the direction of its movement while being spun by said belt, a plurality of substantially U-shape members positioned at spaced intervals along the length of and overlying said belt, the closed ends of each of said members being freely pivoted and having its leg portions extending in the direction of the movement of said belt and into the path of the containers advancing thereon, the distal end portions of said leg being arcuately curved to allow said cans to pass thereunder in their said advance along said belt and to limit the backward movement of any of said containers downwardly of said belt.

10. An apparatus as claimed in claim 9, wherein there is an adjustable screw mounted near the pivoted end of each of said members and positioned to be contacted by said member to vary the position of the distal ends of its leg portions with respect to said belt.

11. An apparatus for cooling hot-packed rollable containers, and their contents, comprising a plurality of cooling units arranged in series to successively receive a flow of containers, each unit including an inclined belt having a surface adapted to receive said containers in a rollable position thereon, means mounted above said belt directing a cooling medium onto the containers along the length of said belt, means for moving

12

said belt upwardly of its inclinations to cause said containers to spin about their own axes, the inclination of said belt being such as to advance said containers along the belt in the direction of its movement while being spun by said belt, means positioned at spaced intervals along the length of said belt and mounted to allow said containers to pass thereby in their said advance along said belt and limiting the backward movement of any of said containers downwardly of said belt, and conveying means extending between adjacent ends of said units to receive said containers discharged from one unit and to deliver them to the next succeeding unit in a rollable position on the belt of said latter unit and functioning to turn said containers endwise, while being passed from one unit to the other, to agitate the contents of the containers endwise of the containers.

10 12. An apparatus for cooling hot-packed rollable containers, and their contents, comprising a plurality of cooling units arranged in series to successively receive a flow of containers, said cooler units each including means to spin said containers about their own axes while being advanced therethrough, and conveying means extending between adjacent ends of said units to receive said containers discharged from one unit and to deliver them to the next succeeding unit in a rollable position on the belt of said latter unit and functioning to turn said containers endwise while being passed from one unit to the other to agitate the contents of the containers endwise of the containers.

15 13. An apparatus as set forth in claim 12, wherein said conveying means includes a container twister-guide having its intake end elevated to receive said containers from a preceding unit and declining to its discharge end.

20 14. An apparatus as set forth in claim 12, wherein the discharge end of a preceding unit is at a higher elevation than the receiving end of a succeeding unit, and wherein said conveying means is a twister-guide through which said containers gravitate and form to alternately turn said containers endwise to opposite positions during their passage therethrough, whereby to agitate the contents in said containers endwise of the latter.

25 15. An apparatus for cooling hot-packed containers, and their contents, comprising a plurality of cooling units arranged in series to successively receive a flow of containers, the discharge end of a preceding unit being at a higher elevation than the receiving end of a succeeding unit, means advancing said containers through each unit, and a twister means between adjacent ends of adjacent units for changing the endwise position of said containers and positioned to receive said containers discharged from a preceding unit and declining to deliver said containers to a succeeding unit, whereby to agitate the contents in said containers endwise of the latter, each of said cooling units including container spinning means and a liquid cooling medium distributing means.
